UNITED STATES PATENT OFFICE.

JOHN W. COVER, OF TACOMA, WASHINGTON.

GRINDING-MILL.

1,194,717.

Specification of Letters Patent. Patented Aug. 15, 1916.

Application filed November 16, 1915. Serial No. 61,847.

To all whom it may concern:

Be it known that I, JOHN W. COVER, a citizen of the United States, and resident of Tacoma, Pierce county, Washington, have invented certain new and useful Improvements in Grinding-Mills, of which the following is a specification.

My invention relates to grinding mills, and particularly to mills which are used extensively in grinding ores. These mills are however adapted for grinding materials of other kinds.

The object of my invention is to improve the construction of such mills so as to increase their efficiency, make them more easy of repair and keeping in order, increase their capacity and reduce the power required to run them.

Other objects will appear from a study 20 of these specifications and the accompanying drawings.

The features of the device as herein shown and described, which I consider novel and upon which I desire patent protection, will 25 be defined in the claims which terminate this specification.

In the accompanying drawings I have shown my invention in the form of construction which I now prefer to use. It is not, 30 however, to be understood that my invention is to be limited to the exact construction herein shown and described.

Figure 1 is a side elevation of a complete mill. Fig. 2 is an end elevation of the same mill. Fig. 3 is a central longitudinal section on a vertical plane. Fig. 4 is a section through the mill taken on a vertical plane which is perpendicular to the axis of the mill. Fig. 5 is a vertical axial section of a 40 modified construction. Fig. 6 is an end view, partly in section. Fig. 7 is a section taken alongside plate 87 of Fig. 5; and Fig. 8 is a view of the opposite end of the mill of Fig. 5.

This mill, in its general character, comprises a drum or cylinder which is mounted 45 to turn upon its axis and which has a series of circular seats carried by its heads, these being arranged in pairs, in which seats are placed rods or bars, the bars of each group being sufficient in number to fill a material 50 part of the cross sectional area of their seats, and yet loose enough to permit rather free rolling or tumbling to take place in each group as they are carried about the central axis by the turning of the drum or

cylinder. While this general feature is not now broadly new, I have made certain improvements in construction which contribute materially to the perfection of the machine 60 and its operation.

The main part of the drum proper, consists of two heads 1, and a metal sheet 2, which connects the heads. The heads are preferably composed of cast iron, while the connecting sheet is composed of rolled metal. The heads at each end are, or may be, alike in construction. Each has a centrally placed hollow sleeve or neck, 10, making a large opening through which the material being 65 operated upon may be inserted and discharged. Upon the outer end of this neck is formed an external trackway or wheel surface, 12, which bears upon carrying 70 wheels 5, of which two are placed under 75 each end of the drum. These wheels are journaled in brackets 50, or any other suitable type of frame. They are also preferably provided with slight flanges to prevent displacement of the drum axially.

Each neck 10 has been shown as provided 80 with external lugs 13, located at about the middle of its length, to which a sprocket or chain wheel may be bolted, thereby providing means whereby power may be applied 85 to turn the drum. It is however, not necessary to apply the chain wheel to more than one end.

Each head has a flange 14 projecting in 85 an axial direction at its outer edge. The 90 sheet metal body 2 is secured to these flanges. Between the neck 10 and the outer edge of the head, it is provided with a series of round holes in which bushings are placed 95 for the reception of the grinding bars. These holes in opposite heads are placed in alinement, so that the rods, when in place, are parallel with each other and the axis of the drum.

The bushings consist of rings 3, of cast 100 iron of sufficient length axially, to provide a proper bearing surface for the ends of the rods. These rings, or their inner surface, may be chilled or otherwise treated to give them a wear-resistant surface; or they 105 may be made of special material. They are provided with a flange 30 of sufficient depth to engage the outer face of the head to thereby fix them in position. The inner surface of these rings or bushings, may be made 110 smooth, or with corrugations or irregularities, as shown at 35, to insure that there can

be no sliding of the bars over the surface of the rings, but that they shall be raised until the upper surface of the pile gets inclined to such a degree that the uppermost 5 will roll over the others, thereby producing a grinding and powdering of the materials which may be caught between them.

The openings of the rings or bushings are closed by plates, 32. Plates 32 and bushings 10 3, have slots 33 extending inward from their outer edge, for the reception of securing bolts 34, which are secured in the head. By taking off one of these plates the bars of any group may be examined, removed and 15 replaced at will.

The drum has a series of openings 20 which are covered by screens 22 contained in frames 21 which are removably secured on the outside of the drum. These openings 20 are so placed with relation to the bushings which contain the bars 4, that they are just above a group of the bars 4 at that side of the drum which is moving upward when turning. At the edges of these screen openings which are lowermost under the same 25 conditions, a narrow deflecting plate 24 is secured, projecting inwardly from the shell of the drum. The projection of this is enough that material dropped therefrom 30 will fall upon the next following group of bars. In this way the feeding of the material within the drum upon the bars is secured.

Each head has radially disposed ribs or 35 lugs 18 upon its inner side, extending substantially from its outer edge to the neck 10. These ribs may be placed opposite the external ribs 11. One function of these ribs is to strengthen the head. Those at the inner side of the head have another purpose. 40 They are placed midway between the seats for the bars and have plates 25 secured thereto and extending from head to head. These plates serve as stiffening members 45 of the drum and also as deflecting plates to direct material dropping from each group of bars upon the fixed central screen 6. This central screen is supported upon two bars 62 which extend through the drum within 50 the opening of the necks 10, these bars may be supported externally of the drum in any suitable manner. It is preferably inclined toward each side so as to deposit all material which will not pass through its mesh, 55 upon the groups of bars. Discharge chutes 61, placed beneath the screen 6, discharge the finely ground material which passes the mesh of screen 6, without the drum. The material which is discharged through the 60 screens 22 in the outer shell of the drum, is collected by the pan 7 which extends beneath the drum.

To prevent drip from running out the neck openings, the inner ends of the necks 65 are made to extend inward a slight distance

and are tapered inwardly, as is shown by the flange 15.

The central screen 6 is mounted to slide lengthwise upon the bars 62, so that it may be removed and replaced at will without affecting any other part of the mill. In operating the mill the pan or tank 7 into which the lower side of the drum dips is kept filled with water to such a point that the lowermost of the groups of grinding bars 75 are more or less submerged.

Another modification of construction is shown in Figs. 5 to 8. In this webs or diaphragms 8 are provided between the heads, in which the bushings 3 are mounted. These 80 are provided with lugs 80 for attachment to the outer shell and are cut away, as at 81, between these lugs, thus preventing their acting as cut-offs for the materials in the drum.

In Figs. 5 and 8 I have shown screens 85 of segmental shape at the ends of the drum. These screens are placed at the outer side of angularly projecting hoods 86, so that when one of these reaches the bottom of the drum 90 the screen surface faces downwardly. With this type of construction the tank 7 would not ordinarily be used.

Where screens are used upon the ends of the drum, it is desirable to keep the ends of 95 the grinding rods from engaging with the drum heads. I then employ a diaphragm or plate 87 which is secured a short distance inward from the head and against which the ends of the grinding rods 4 abut. Such 100 a diaphragm may be placed at each or at only one end of the drum, as desired. One of the heads is preferably provided with hand holes, ordinarily covered by plates 88, giving access each to two of the groups of 105 grinding bars 4.

What I claim and desire to secure by Letters Patent is:

1. A grinding mill comprising a drum mounted to be rotated and containing a series of pockets annularly disposed within its outer shell, a series of grinding rods loosely placed within each pair of pockets, radially placed deflecting plates between the sets of grinding rods, and a fixed screen 110 lying in the central part of the drum in position to receive the discharge from said deflecting plates.

2. A grinding mill comprising a drum mounted to rotate, a series of circular pockets secured in pairs to opposite heads, and spaced about the outer part thereof, grinding bars loosely grouped in said pockets, screens placed in the periphery of the drum between each group of grinding bars and to 120 be beneath a radial plane between said groups at the side of the drum which is moving upward, deflecting plates connecting opposite heads and radially placed between each group of grinding bars, said 125 130

plates having their outer edges spaced inward from the outer shell of the drums.

3. A grinding mill comprising a drum mounted to rotate, a series of circular pockets adapted to serve as seats for the grinding bars and placed about the outer zone of the drum, grinding bars seated in said pockets, deflecting plates radially placed between each group of grinding bars and having 10 their outer edges spaced inward from the outer shell of the drum, the outer shell of the drum having screened openings between each group of grinding bars and at one side of the plane of the corresponding deflecting plate, and a plate extending inward from the shell at the other side of said screen openings from that of said deflecting plate.

4. A grinding mill comprising a drum having a series of groups of grinding bars

constrained to occupy as a whole a definite 20 position in the drum and free to roll or move upon each other within the limits of their position, the outer shell of the drum having screens therein and inwardly projecting flanges along one edge of said screens, radially positioned deflecting plates between the groups of grinding bars having their outer edges inward from the outer shell and substantially aligned with the other edge of the screens in the outer shell, a screen occupying the space within the groups of grinding bars and a discharge chute beneath said centrally placed screen and extending without the drum through axial openings thereof.

Signed at Seattle, Washington, this 28th day of October, 1915.
